UNITED STATES PATENT OFFICE

CARL F. HAAS, OF SOUTH BEND, INDIANA, ASSIGNOR TO WESTINGHOUSE ELECTRIC
AND MANUFACTURING COMPANY, A CORPORATION OF PENNSYLVANIA

DESIGN FOR A HEAD FOR LIGHTING UNITS

Application filed December 7, 1929. Serial No. 33,688. Term of patent 14 years.

To all whom it may concern:

Be it known that I, CARL F. HAAS, a citizen of the United States, residing at South Bend, in the county of St. Joseph and State of Indiana, have invented a new, original, and ornamental Design for a Head for Lighting Units, of which the following is a specification, reference being had to the accompanying drawing, constituting a part hereof.

Figure 1 is a front elevational view of a

head for a lighting unit showing my new design and,

Fig. 2 is a side elevational view of the head shown in Fig. 1.

I claim:

The ornamental design for a head for lighting units substantially as shown.

In testimony whereof, I have hereunto subscribed my name this 4th day of Dec., 1929.

CARL F. HAAS.
